UNITED STATES PATENT OFFICE.

LOUIS BLAND, OF SCHENECTADY, NEW YORK.

ADJUSTABLE FRAME.

1,108,123.

Specification of Letters Patent. Patented Aug. 25, 1914.

Application filed March 4, 1912. Serial No. 681,538.

To all whom it may concern:

Be it known that I, LOUIS BLAND, citizen of the United States, residing at Schenectady, in the county of Schenectady and State 5 of New York, have invented certain new and useful Improvements in Adjustable Frames, of which the following is a specification.

This invention relates to improvements in frames of the class adapted to be adjusted to fit various sizes of pictures, such as prints, 10 photographs, and the like, and has for one of its objects to simplify and improve the construction and increase the efficiency and utility of devices of this character.

15 Another object of the invention is to provide a simply constructed device which may be formed of any suitable material and of any required size and which may be readily adapted without structural change to photographs and other pictures of varying sizes 20 and proportions.

Another object of the invention is to provide a device of this character which may be quickly adjusted and attached to or removed 25 from the picture and without injuring the latter.

Another object of the invention is to provide a device of this character wherein provision is made for securing the device to a 30 wall or the like support by the same fastening devices whereby the frame is secured to the backing.

Another object of the invention is to provide a device of this character wherein provision is made for protecting the corners and 35 preventing the displacement of the holding devices.

With these and other objects in view, the invention consists in certain novel features 40 of construction as hereafter shown and described, and then specifically pointed out in the claims, and in the drawings illustrative of the preferred embodiment of the invention.

45 Figure 1 is a front elevation of one of the improved frames; Fig. 2 is a side elevation of the same; Fig. 3 is a view enlarged on the line 3—3 of Fig. 1; Fig. 4 is an enlarged sectional detail on the line 4—4 of Fig. 1; Fig.

50 5 is a detached perspective view of one of the corner guards from the rear; Fig. 6 is a view similar to Fig. 4 illustrating a modification in the construction.

Corresponding and like parts are referred 55 to in the following description and indi-

cated in all the views of the accompanying drawing by the same reference characters.

The improved frame may be constructed of any suitable material and embodies four L-shaped overlapping members 10 provided with loops or keepers 11 which slidably couple the members. One of the keepers is attached to each of the frame members and bears loosely around the adjacent member permitting the latter to slide therethrough. 60 By this simple means a frame is constructed which may be collapsed or reduced in size until the keepers engage against the L-shaped member at their elbows, or extended 65 until the keepers on each of the overlapping pairs of frame members closely engage at the terminals of the members. Thus the frame may be adjusted to any required size within the range of movement of the 70 slideable members. It will be noted that the keepers maintain a "balanced" position 75 relative to each other and to the frame members no matter to what extent the frame members may be adjusted. Thus the presence of the keepers does not detract from 80 the appearance of the frame, but on the contrary increases the ornamental appearance. At the corners or "elbows" of the L-shaped members suitably constructed fastening devices are employed, such as thumb-tacks 12, 85 to secure the frame members to a backing represented at 13. The head of the thumb-tack portion of the device is covered by an ornamental shield 14 as shown in Fig. 1, which thus not only adds a "finish" to the 90 frame to improve the appearance but likewise protects the thumb-tacks from accidental displacement and protects the corners 95 of the frame. Each of the corner shields is formed from a single piece and comprises an outer approximately triangular body portion folded over along the edges of the sides of the triangular body portion, as shown in Fig. 5, to form flanges 14^a embracing the frame members as shown. The corner members are thus retained in position by friction only, the rear or folded-over portions being "clenched" upon the material of the frame 100 members.

It will be seen that these corner pieces 105 perform four functions. The triangular body portion which extends across the face of the frame forms an ornamental finish to the frame itself. The triangular body portion is of ornamental or embossed configu- 110

ration so as to form a pocket housing entirely covering the head of the thumb tack or push pin 12, and thus when the corner piece is in place it prevents the accidental 5 loosening of the thumb tack or push pin. The ornamental corner piece also tends to prevent anyone from mischievously withdrawing the thumb tack or push pin as the head of the pin is entirely concealed, and the 10 insertion of a finger nail beneath the angular edge of the body of the corner piece would not act to withdraw the pin. The flanges 14^a extend at right angles to each other and meet at the point where the shank of the 15 pin enters the material of the frame. As a consequence the edges of the flanges 14^a reinforce the material of the frame and prevent its being torn out, that is, prevent the perforation through which the shank of the 20 push pin passes from becoming enlarged by the weight of the frame and picture.

In applying the improved device the frame members are adjusted to correspond to the picture to which the frame is to be 25 applied and a backing member 13 of wood, heavy pasteboard, or other material, cut to correspond to the outlines of the frame, and the frame secured to the backing by forcing the thumb-tacks or other fasteners into the 30 same after the photograph has been disposed in position to be covered, and held in place at its edges by the frame. If preferred the securing devices 12 may be of sufficient length to project through the backing 13 to 35 a sufficient extent to enter a wall or like support indicated at 15, so that the frame and its contents may be temporarily supported in position.

The improved device is simple in construction, can be inexpensively manufactured of 40 light cardboard or other thin and light material, and readily adapted to prints, cuts, photographs, and other like articles.

The improved device will be especially 45 useful for displaying photographs, or other illustrations temporarily for advertising purposes, and may also be used as a permanent frame for suspension upon a wall.

The keepers 11 may be of any suitable material, corresponding to the material of the frame, or stamped from material and polished, or otherwise ornamented as may be desired.

Having thus described the invention what 50 is claimed as new is:—

1. The combination with a frame adapted to lie upon the face of the picture to be framed, of push pins projecting through the corners of the frame and picture and

adapted to engage a support, said pins having flat heads lying upon the face of the frame, and detachable guards, each guard embracing one corner of the frame, the body of the guard extending over and bearing against the head of a corresponding pin and holding it in place, the body of the guard being provided with portions angularly arranged with relation to each other and engaging over the adjacent edges of the corner of the frame to embrace the same. 60

2. A frame comprising a plurality of co-acting frame members arranged to overlap and slidably engage, a headed pin extending through each of said frame members and adapted to engage in a support, and guards 65 embracing the corners of said frame members and bearing respectively over the heads of said pins. 70

3. A frame comprising a plurality of co-acting frame-members arranged to overlap 80 and slidably engage, a backing member of fixed dimensions, and a pin projecting from each of said frame members for engaging said backing member.

4. The combination with a frame, of push 85 pins projecting through the corners of the frame and adapted to engage a support, said pins having heads lying upon the face of the frame, and corner pieces forming guards and embracing each one corner of the frame, 90 each corner piece comprising a triangular face portion enlarged at its middle to form a cover for the head of the pin, and rearwardly and inwardly bent portions formed integral with the first named portion and 95 embracing the side edges of the frame and extending over the rear face thereof.

5. The combination with a frame, of a push pin extending through the frame at the corner thereof, and having a head bearing upon the outer face of the frame, and a guard comprising an approximately triangular body portion lying upon the face of the frame and bearing against and housing the head upon the pin, the material along 100 the whole extent of two sides of the body portion being bent over to form flanges 105 engaging beneath the sides of the corner of the frame, said flanges being less in width than the distance between the push pin and 110 the adjacent edge of the frame.

In testimony whereof I affix my signature in presence of two witnesses.

LOUIS BLAND. [L.S.]
